UNITED STATES PATENT OFFICE.

ANTON A. PETERSON, OF SUNDALH, MINNESOTA.

DEVICE FOR TRANSMITTING POWER.

SPECIFICATION forming part of Letters Patent No. 651,769, dated June 12, 1900.

Application filed August 22, 1899. Serial No. 728,125. (No model.)

To all whom it may concern:

Be it known that I, ANTON A. PETERSON, a citizen of the United States, residing at Sundahl, in the county of Norman and State of Minnesota, have invented a new and useful Device for Transmitting Power, of which the following is a specification.

This invention relates to devices for transmitting power, and is designed particularly for running threshing-machines. In running threshing-machines it is common to transfer the power and motion from the engine to the cylinder of the machine by a band running on the driving-pulley of the engine and on a pulley on the shaft of the cylinder of the threshing-machine or on a shaft geared thereto, and on account of the danger of fire being communicated from the fire-box or smoke-stack of the engine to the straw the threshing-machine is usually stationed at considerable distance from the engine, and the power-transmitting belt is therefore a long one and commonly consists of a band several inches in width. Much annoyance occurs by reason of the sagging of the belt and its liability to slip on the pulleys, as well as by the belt being caught by the wind and thrown off the pulleys or so jerked and twisted as to interrupt a steady and reliable movement of the cylinder.

One object, therefore, of the present construction and arrangement is to provide a rope or cable drive for the class of machinery stated, including devices having adjustable features and means for preventing slipping of the rope or cable and also permitting it to be positively held in operative relation and also to afford means for arranging the engine at an angle to the end of the thresher without detracting in the least from the effectiveness of the power-transmitting devices.

Other objects and advantages will be disclosed in the subjoined description and the novel features set out in the claims, and an embodiment of the preferred form of the improved devices is illustrated in the accompanying drawings and susceptible of changes in the proportions, size, form, and minor details of construction, which fully fall within the purview of the invention, and in which—

Figure 1 is a top plan view of a part of a threshing-machine and engine-frame, show-

ing the improved devices applied thereto. Fig. 2 is a horizontal section through the devices applied to the cylinder-shaft and showing a sectional form of pulley. Fig. 3 is a top plan view of one of the sectional pulleys partially broken away. Fig. 4 is a detail perspective view of one of the pulleys. Fig. 5 is a face-section through a portion of the improved drive-wheel. Fig. 6 is a transverse vertical section of a part of the improved drive-wheel. Fig. 7 is an elevation of a part of the threshing-machine and support for the drive-wheel, showing the improved devices in relative position and particularly illustrating a change in the arrangement of the direction-pulleys.

Similar numerals of reference are employed to indicate corresponding parts in the several views.

The numeral 1 designates a threshing-machine of any preferred form and which will have the usual necessary appurtenances, including a cylinder and concave and a cylinder-shaft 2, projecting outwardly from one side. The improved devices, as before intimated, are particularly intended for transmitting power from an engine, though they are equally well adapted for use in connection with other power-generating mediums. In the drawings, however, a part of an engine-frame 3 is shown, which gives bearing to a drive-shaft 4, and on the latter is fixed to rotate therewith the improved form of drive-wheel 5. This drive-wheel structurally includes a central body 6, of suitable material, on the periphery of which are fastened a series of grooved ring-sections 7, which are held in place against slipping and disconnection from the body 6 by keys 8, fast on the said body and interposed between contiguous ends of the said sections 7 and are secured by adhesive material or any suitable interposed fastenings. The keys 8 are grooved similarly to the sections 7, and by this means a body 6 of inferior material may be caused to practically serve the purpose in conjunction with a surrounding ring or bearing-surface of superior material. The sections 7 at points intermediate the ends have yielding grips 9 projecting outwardly therefrom and consisting, essentially, of U-shaped plate-springs having their ends flared and bent

down or inwardly and adapted to receive the rope or cable 10 and prevent slipping of the same on the drive-wheel or disengagement from the latter.

- 5 On the cylinder-shaft 2 pulley-sections 11 and 12 are adjustably mounted and have their inner opposing or adjacently-situated peripheral corners cut out a preferred depth to provide angular grooves 13. These grooves 10 13 unitedly form a space for the reception of the rope or cable 10. Each of the sections 11 and 12 has a bore 14 extending therethrough and of a diameter considerably in excess of that of the shaft 2, and projecting 15 outwardly from the face of each section opposite that in which the grooves 13 are formed are a pair of parallel arms 15, pivotally connected to diametrically-opposite portions of heads 16, which have set-screws 17 20 extending therethrough in planes at right angles to the points of attachment of the said arms to adjustably hold the sections on the cylinder-shaft. By the pivotal connection of the arms 15 to the heads 16 the pulley-sections 25 are allowed to move inward and outward to and from the shaft as far as the dimensions of the bores 14 will permit.

In arranging the rope or cable 10 in connection with the improved devices it is first run 30 around the drive-wheel 5 and the opposite portions brought to bear against direction-pulleys 18, which may be arranged in horizontal planes, as shown by Fig. 1, with the upper faces parallel or in the same plane, or, 35 as illustrated by Fig. 7, said pulleys can be disposed one above the other, and in either instance are held on suitable supports. The rope or cable is then applied to the space between the contiguous portions of the pulleys 40 11 and 12 formed by the grooves 13, and as the drive-wheel is rotated the rope or cable is correspondingly actuated and power thereby transmitted to the cylinder-shaft 2 through the medium of said sectional pulley. The 45 movement of the sections 11 and 12 inward toward or outward from the shaft 2 will occur automatically and to a degree proportionate to the tension or drag of the rope or cable thereon. By this means the shaft 2 is adapted 50 to receive rope or cable belts of various gage. The movement of the pulley-sections will not cause a wear on the shaft 2, as the inner faces of the said sections will be so close together that it will be impossible for the inner portions 55 of the said sections to touch the said shaft. Slipping of the rope or cable on the pulley-sections will be prevented by the ad-

justment set forth, in view of the fact that at the point of the greatest pressure of the rope or cable said sections will be pulled to reduce 60 the space normally established by the grooves 13. This will contract the rope or cable groove and cause the opposite walls of the latter to come closer to the rope or cable. The pulley-sections may be unitedly shifted on 65 the shaft 2 by loosening the screws 17 and pushing against either head 16 in accordance with the direction of movement desired and the said sections afterward fixed by retightening the screws. It is also obvious that the sections may be separated, as before stated. 70

By the introduction of the direction-pulleys 18 the engine may be placed at any angle relatively to the threshing-machine, as clearly indicated in the drawings. The positive operation arising from the use of the improved attachment is of material importance, and the simplicity of construction, together with the advantages accruing therefrom, makes the improvement of valuable acquisition to the art to which it pertains. 75

Having thus described the invention, what is claimed as new is—

1. In a device of the character set forth, the combination with a shaft, of heads thereon 85 spaced apart from each other, and pulley-sections pivotally attached to said heads.
2. In a device of the character set forth, the combination with a shaft, of heads thereon 90 spaced apart from each other, and pulley-sections pivotally attached to said heads and having inner grooved corners which initially form a receptive space for a rope or cable, and openings therethrough of a greater diameter than that of the shaft. 95
3. In a device of the character set forth, the combination with a shaft, of oppositely-disposed heads adjustably fixed thereto, and grooved pulley-sections having arms pivotally connected to said heads. 100
4. In a device of the character set forth, the combination with a shaft, of freely-movable pulley-sections thereon having openings therethrough of greater diameter than that of the shaft and adapted to be engaged by a rope 105 or cable belt.

In testimony that I claim the foregoing as my own I have hereto affixed my signature in the presence of two witnesses.

ANTON A. PETERSON.
